CURRENT CONVERTING SYSTEM

Fenton F. Hutchinson, San Francisco, Calif., assignor to Kohler & Chase, San Francisco, Calif., a corporation of California

Application August 29, 1938, Serial No. 227,332

6 Claims. (Cl. 175—364)

The invention, in general, relates to means for supplying alternating current from a direct current source. More particularly, the invention relates to a current converting system affording distribution or allotment of the current at predetermined time intervals in predetermined quantities.

In all current converting systems presently in use, it is the conventional practice to make use of external resistance of some character, such as resistors, condensers, reactances, or the like, to take care of load variations. Moreover, the selection and arrangement of such resistors or combination of resistors and condensers has effective results in the production of desired wave forms for meeting various industrial applications. Under certain load conditions, a relatively high degree of efficiency maintains in many current converting systems while under load conditions where the variations are appreciable the efficiency of the system materially decreases because the resistors and condensers employed cannot withstand such extreme load variations, and must be frequently replaced. Moreover, it is customary to design resistors and condensers for use with fairly constant loads as well as for effecting desired wave forms under such conditions of operation. Due to the use of such designed resistors and condensers, relatively wide variations in load result in distortion of the wave form and unsatisfactory performance.

It is a primary object of my invention to provide a current converting system which affords efficient performance under relatively wide load variations without the use of external resistance.

Another object of the invention is to provide a current converting system of the indicated character embodying means for allotting or distributing current at predetermined time intervals and in predetermined quantities regardless of load variations.

A still further object of my invention is to provide a system of the aforementioned character which also is adapted to produce predetermined and variable current and voltage wave forms without the use of external resistance.

Other objects of the invention, together with some of the advantageous features thereof, will appear from the following description of a preferred embodiment of my invention which is illustrated in the accompanying drawing. It is to be understood that I am not to be limited to the precise embodiment of the invention shown in the drawing, as my invention, as defined in the

appended claims, is adaptable for embodiment in a plurality and variety of forms.

Referring to the drawing:

The single figure is a diagrammatic view of a preferred embodiment of the invention. 5

In its preferred form, the current converting system of my invention preferably comprises a source of direct current, means for supplying alternating current from said direct current source including an electrical circuit comprising a commutator divided into a plurality of segments electrically insulated from one another and electrically connected together in pairs, a rotatable brush connected to one side of said direct current source and adapted to engage successive segments of said commutator at predetermined time intervals, together with a transformer having a mid-point tap electrically connected to the other side of said direct current source and having a plurality of taps on each side of said mid-point tap dividing said transformer into an equal number of sections on each side of the center thereof, and electrical conductors between said segments of said commutator and said plurality of taps on said transformer for distributing the current in predetermined quantities at predetermined time intervals upon rotation of said brush. 25

As illustrated in the accompanying drawing, I provide a direct current source 11, such as a conventional storage battery, together with an electrical circuit including a commutator 12 divided into a plurality of segments 13, preferably an even number, which are electrically insulated from one another in the usual manner by suitable strips 14 of insulation material. It is to be appreciated that in applications of the converter of my invention to relatively light loads a converter having a commutator with fewer segments 13 may be used and a single brush employed rather than the number of segments shown in the commutator illustrated in the drawing and rather than the two brushes shown. In the particular embodiment of the invention shown in the drawing, I have divided the commutator into forty segments 13 and arranged the same in quadrants 16, 17, 18 and 19, as indicated by the reference letters AB, BC, CD and DA, and I have also provided a separator bar 21, which conveniently may be termed a "dead" bar, between each quadrant of segments, although these dead bars are not essential. 45

In accordance with the invention, one side of the direct current source 11 is electrically connected by a lead 22 to the commutator brushes 23 which preferably are mounted on the inside of 55

the annulus containing the segments 13 and on a metal block 24 keyed or otherwise secured to a driven shaft 26. It is, of course, optional to mount the brushes inside of the annulus as they can be mounted outside thereof, if desired, with equal results. The mounting of brushes 23 is such that the brushes engage segments 13 of the commutator under the action of centrifugal force upon rotatable movement of the brushes when the shaft 26 is rotated. Suitable pins 25 are provided on metal block 24 to limit the inward movement of brushes. The other side of the direct current source 11 is electrically connected by means of a lead 27 to a mid-point tap 28 of a transformer 29 which preferably is a conventional metal core transformer of the standard type having the core 31 built up of laminations to reduce eddy currents to a minimum.

As illustrated, I divide transformer 29 into a plurality of sections, preferably equal in number on each side of mid-point tap 28, by tapping the transformer as at 32, 33, 34, 36, 37, 38, 39 and 41. In the particular embodiment of the invention illustrated, I have provided five sections on each side of the center tap 28 but it is to be understood that I am not to be limited to the number of sections in which the transformer may be divided nor to the number of segments into which the commutator 12 may be divided. The various sections of transformer 29 are electrically connected to the segments 13 of the commutator 12, by groups, as shown. Thus, the first segment 13 of quadrant 16 of the commutator, i. e., the first segment to the right of the top center of the commutator, as indicated by the reference letter "A", is connected by a lead 42 to one end 43 of transformer 29 and such segment 13 is also connected, by means of a conductor 44, to the last or tenth segment 13 of quadrant 16. Moreover, I provide a jumper bar 46 leading from such last or tenth segment 13 of quadrant 16 to lead 42 thus electrically connecting the first and tenth segments 13 of quadrant 16 of the commutator, as a pair, to the end 43 of the transformer 29. Similarly, I provide electrical connections joining the second and ninth segments 13 of quadrant 16 of the commutator 13 to the transformer, but to a section tap thereof rather than to the end 43. As shown, I provide a lead 47 connecting the second segment of quadrant 16 to section tap 41 of the transformer; a conductor 48 connecting such second segment to the ninth segment of quadrant 16; and a jumper bar 49 connecting the ninth segment to the lead 47 so as to connect the second and ninth segments 13 of quadrant 16 of the commutator, as a pair, to the transformer 29 at section tap 47. Likewise, I electrically connect the third and eighth segments of quadrant 16, as a pair, to the transformer 29. These connections include a lead 51 from the third segment to a section tap 39 of the transformer; a conductor 52 joining the third segment with the eighth segment; and a jumper bar 53 from the eighth segment to lead 51. Similarly, the fourth and seventh segments of quadrant 16 of the commutator are electrically connected, as a pair, to the transformer 29. The connections for the fourth and seventh segments include a lead 54 connecting the fourth segment to section tap 38 of the transformer; a conductor 56 joining the fourth and seventh segments; and a jumper bar 57 leading from the seventh segment to the lead 54. The fifth and sixth segments of quadrant 16 are also electrically connected as a pair to the transformer and, accord-

ingly, I provide a lead 58 connecting the fifth segment to section tap 37 of the transformer; and a jumper bar 59 connecting the sixth segment of quadrant 16 to the lead 58, there being no need for a conductor between the fifth and sixth segments as the brush 23 is sufficient in width to span the segments and effect the electrical connection. Thus, the fifth and sixth segments 13 of quadrant 16 of the commutator also are connected, as a pair to the transformer 29 through section tap 37 thereof.

In a like manner, the segments 13 of quadrant 19 of the commutator 12 are electrically connected, in pairs, to the transformer 29 by sections. Quadrant 19 of the commutator conveniently is marked out in the drawing by the reference letters DA. The first segment of quadrant 19, i. e., the segment to the left of the top center of the commutator indicated by reference letters "A", is electrically connected by means of a lead 61 to the end 62 of the transformer 29; a conductor 63 joins the first segment to the tenth segment of quadrant 19; and a jumper bar 64 joins the tenth segment to lead 61. Similarly, the second segment and ninth segment of quadrant 19 are joined, as a pair, to a section of transformer 29. To effect this connection, I provide a lead 66 from the second segment to section tap 32 of the transformer; and a jump bar 68 connecting the ninth segment to lead 66. Likewise, the third and eighth segments of quadrant 19 are electrically connected, as a pair, to another section of transformer 29. The connections for this pair include a lead 69 from the third segment to section tap 33 of the transformer; a conductor 71 joining the third and eighth segments; and a jump bar 72 from the eighth segment to the lead 69. Similarly, the fourth and seventh segments of quadrants 19 are electrically paired together and connected to a section tap of the transformer. The electrical connections for this pair of segments include a lead 73 from the fourth segment to section tap 34 of the transformer; a conductor 74 joining the fourth to the seventh segment; and a jump bar 76 leading from the seventh segment to the lead 73. The fifth and sixth segments of the quadrant 19 also are electrically connected, as a pair, to the transformer and, to effect this result, I provide a lead 77 from the fifth segment to section tap 36 of the transformer and a jump bar 78 from the sixth segment to the lead 77, there being no need of a conductor between the fifth and sixth segments as the brush 23 spans the two segments and electrically connects the same.

The foregoing connections would be all that would be required for a twenty segment arrangement with one brush. However, in the embodiment of the invention illustrated in the drawing wherein forty segments with two brushes are depicted, I arrange the system so that the segments 13 of diametrically opposite quadrants are grouped in pairs. Thus, the segments of quadrant 18 are electrically grouped in pairs with pairs of segments 13 of quadrant 16, while the segments of quadrant 17 are electrically grouped in pairs with pairs of segments of quadrant 19. Accordingly, I provide a lead 79 which joins the first and tenth segments, as a pair, of quadrant 18 of the commutator to jump bar 46 or, if desired, directly with lead 42 which connects the first and tenth segments of quadrant 16 to the end 43 of the transformer. Similarly, I provide a lead 81 connecting the second and ninth segments of quadrant 18, as a pair, with the connections that join the second and ninth segments of 75

quadrant 16, as a pair, to section tap 41 of the transformer, lead 81, in the embodiment shown, being connected to jump bar 49. Likewise, the third and eighth segments of quadrant 18 are 5 electrically connected as a pair, by means of lead 82 from such eighth segment to jumper bar 53, to the paired third and eighth segments of quadrant 16 which are connected to section tap 39 of the transformer 29 as above described. Similarly, lead 83 from the seventh segment of quadrant 18 of the commutator to lead 54 groups the paired fourth and seventh segments of quadrant 18 with the paired fourth and seventh segments of quadrant 16 which are electrically connected 10 to tap 38 of the transformer. Likewise, the lead 84 from the sixth segment of quadrant 18 to the jump bar 59 groups the paired fifth and sixth segments of such quadrant 18 with the paired fifth and sixth segments of quadrant 16 which are 15 electrically connected with section tap 37 of the transformer 29.

In a like manner, the segments of quadrant 17 are paired together and grouped with the paired segments of quadrant 19 of the commutator. 20 This grouping is effected through leads 86, 87, 88 and 91; lead 86 joining the first and tenth segments of quadrant 17, as paired, to jump bar 64 which connects the first and tenth segments of quadrant 19 to the end 62 of transformer 29 through the lead 61. Similarly, lead 87 joins the ninth segment of quadrant 17 to the jump bar 68 for electrically connecting the second and ninth segments of such quadrant 17, as a pair, to the paired second and ninth segments of quadrant 19 which, in turn, are electrically connected 30 through lead 66 to section tap 32 of the transformer. Likewise, the lead 88 from the eighth segment of quadrant 17 of the commutator to jump bar 72 groups the paired third and eighth segments of such quadrant 17 with the paired third and eighth segments of quadrant 19 which, in turn, are electrically connected through lead 69 and jump bar 72 to section tap 33 of the transformer, as above described. Similarly, lead 89 40 from the seventh segment of quadrant 17 to the lead 73 groups the paired fourth and seventh segments of such quadrant 17 with the paired fourth and seventh segments of quadrant 19, the latter being electrically connected to section tap 34 of the transformer through the lead 73 and jump bar 76. Likewise, the paired fifth and sixth segments of the quadrant 17 of the commutator are grouped with the paired fifth and sixth segments of quadrant 19 through lead 91 which 50 connects to lead 77, the latter, together with jump bar 78, connecting the paired fifth and sixth segments of quadrant 19 with section tap 35 of the transformer.

It may be observed that in accordance with 60 standard practice, an alternating load circuit may be directly connected, as by means of leads 92 and 93, to the ends 43 and 62, respectively, of transformer primary 29. Or, if desired, a secondary coil 94 may be incorporated into the 65 transformer, for stepping up or stepping down the voltage to predetermined values, and leads 96 and 97 employed for connecting the secondary to an alternating current load circuit.

In explanation of the mode of operation of 70 the system of my invention, it may be assumed that shaft 26 is driven at a constant speed and that the shaft rotates in a clock-wise direction. With switch 98 closed, it will be clear that when brushes 23 initially engage the first segment of quadrant 16 and the tenth segment of quadrant

18 of the commutator, a direct current will flow in the established circuit from the direct current source 11 through the brushes 23, thence through the engaged segments 13 and through one-half of the transformer 29 from end 43 5 thereof to the mid-point tap 28 thereof, and thence back to the other side of the direct current source through lead 27. As the brushes continue to rotate in the clock-wise direction, first one section after another of one-half of 10 transformer 29 is cut out of the circuit thus established and then such sections are placed back in the circuit, the current traveling always toward the mid-point of the transformer when operations are on one-half of the transformer. 15 After brushes 23 leave the segments of the quadrants 16 and 18 of the commutator and engage the segments of quadrants 17 and 19, the circuit is established through the other one-half of transformer 29 from one side of the direct 20 current source 11 through brushes 23, the above described electrical connections to the end 62, of the transformer, through the transformer to the mid-point tap 28 and thence through lead 27 back to the other side of the direct current 25 source. As the brushes 23 continue to rotate and successively engage the segments of quadrants 17 and 19, first one section after another of one-half of the transformer are cut out successively and then cut back into the circuit, the 30 current always traveling from end 62 of the transformer toward the mid-point tap 28 when the brushes are engaging the segments 13 of quadrants 17 and 19 of the transformer. Thus, with the brushes 23 rotating at a constant speed, 35 current flows alternately through transformer 29, first in one direction from one end thereof to the mid-point 28 thereof and then in the other direction from the other end of the transformer to the mid-point thereof, and, at the same time, 40 successively cutting out and cutting in the different sections on each side of the center of the transformer as above described. In addition to the supplying of alternating current, direct current also flows in the circuit which is in phase 45 with the alternating current.

Since the current is distributed or allotted by sections, or by commutator segments, at predetermined time intervals, it will be clear that even though the voltage in the circuit rises as each 50 section of the transformer is cut out and lowers again as the sections are cut back in again during each alternation, the circuit will not be shorted since no coils are "bucked" and since the current always flows toward the center tap 55 of the transformer. It also will be clear that, with the arrangement shown, the direct current varies in direct proportion to the value of the alternating current. Since I have eliminated the need for external resistance, the system will 60 function with increased efficiency.

It is possible, with the current converting system of my invention as illustrated, to obtain desired types of wave forms without the use of external resistance. By varying the number of 65 windings per section of the transformer and by varying the number of windings in each section, it is clear that wave forms can be predetermined. The particular type of wave form thus predetermined will not vary with load variations up to the maximum capacity of the converter. By various types of wave forms, I mean that the ordinary type of wave form, commonly known as the sine wave, can be produced as well as the so-called "saw-tooth" wave or the 75

so-called "flat-top" wave, it being generally known in the art that waves of these different types are especially suitable for different applications of converters.

5 It is to be understood that the appended claims are to be accorded a range of equivalents commensurate in scope with the advance made over the prior art.

I claim:

10 1. A current converting system comprising a direct current source, and means for converting said direct current to alternating current; said means including an electrical circuit comprising said direct current source, a commutator divided into a plurality of segments electrically insulated from one another and electrically connected in pairs, a rotatable brush for successively engaging said segments, an electrical connection between said brush and one side of said direct current source, and a transformer having a mid-point tap electrically connected to the other side of said direct current source and divided into a plurality of sections equal in number on each side of said mid-point tap, electrical connections from one group of said plurality of segments of said commutator joining said segments in pairs to different sections of said transformer on one side of said mid-point tap, and electrical connections from another group of said plurality of segments of said transformer joining said segments in pairs to different sections of said transformer on the other side of said mid-point tap.

15 2. A current converting system comprising a direct current source, means for supplying alternating current from said source including a transformer having a mid-point tap connected to one side of said source, a commutator divided into a plurality of segments, and a commutator brush for engaging said segments and connected to the other side of said source, and means for distributing the current in predetermined quantities and at predetermined intervals including leads from electrically paired segments of said commutator to spaced taps on one side of said transformer, and leads from other electrically paired segments of said commutator to spaced taps on the other side of said mid-point tap of said transformer.

20 3. In a current converting system, a trans-

former having a mid-point tap and a plurality of taps dividing the transformer into a plurality of sections taps on each side of said mid-point tap, a commutator divided into a plurality of segments, electrical connections between electrically paired segments of said commutator and said section taps on one side of said mid-point tap of said transformer, and electrical connections between other electrically paired segments and said section taps on the other side of said mid-point tap of said transformer.

25 4. In a current converting system, a transformer having a mid-point tap and a plurality of taps on each side of said mid-point tap dividing said transformer into a plurality of section taps on each side of the center thereof, a commutator divided into two sets of segments grouped opposite to one another, electrical connections between segments of each set to group the segments of each set in pairs, electrical connections between electrically paired segments of one set to the section taps of said transformer on one side of the mid-point tap thereof, and electrical connections between electrically paired segments of the other set and the section taps of said transformer on the other side of said mid-point tap.

30 5. A method of supplying alternating current from a direct current source and of distributing the current in predetermined quantities at predetermined time intervals, said method consisting of causing current alternately to flow through one side of a transformer toward the center thereof in sections of the transformer and to flow through the other side of the transformer toward the center thereof in sections of the transformer.

35 6. A method of supplying alternating current from a direct current source and for allotting the current in predetermined quantities and at predetermined time intervals, said method consisting of causing current successively to flow through one-half of a transformer and then sections of said one-half of the transformer always in a direction toward the center of the transformer, then successively to flow through the other half of the transformer and then through sections of said other half of the transformer in a direction always toward the center of the transformer.

FENTON F. HUTCHINSON.
